UNITED STATES PATENT OFFICE.

RUBEN E. ROSENBERGER, OF DEWEY, ARIZONA.

CLOTHES-PIN.

1,257,639.

Specification of Letters Patent. Patented Feb. 26, 1918

Application filed August 11, 1916. Serial No. 114,424.

To all whom it may concern:

Be it known that I, RUBEN E. ROSENBERGER, a citizen of the United States, residing at Dewey, in the county of Yavapai 5 and State of Arizona, have invented certain new and useful Improvements in Clothes-Pins, of which the following is a specification.

This invention has relation to clasps of 10 the coacting jaw type and has for an object to provide a clasp in which the jaws are formed of wire held in pivotal relation by plates forming the balance of the clasp.

Another object of the invention is to form 15 a clasp of the character described which may be readily and cheaply made and adapted to support clothes or the like from a line or similar support.

In addition to the foregoing, my invention 20 comprehends improvements in the details of construction and arrangement of parts to be hereinafter described and particularly pointed out in the appended claim.

In the accompanying drawings in which 25 similar and corresponding parts are designated by the same characters of reference throughout the several views in which they appear:

Figure 1 is a view in side elevation of a 30 clasp constructed after the manner of my invention.

Fig. 2 is a longitudinal section there- 35 through.

Fig. 3 is a view thereof in plan.

Fig. 4 is view thereof in rear elevation, 40 and

Fig. 5 is a view similar to Fig. 4, but illustrating a modification.

With reference to the drawings, 1 indi- 45 cates the clamping jaws of my improved clasp, formed of sections of wire bent to substantially U-shape, with the intermediate curved portions 2 thereof adapted for mutual contact to grip articles therebetween.

45 The parallel strands of wire thus formed are bent intermediate their ends and the curved portion, as indicated at 3, to further space apart the terminals of the members. The terminals of each member are further con- 50 nected by means of plates or the like 4, crimped at opposite longitudinal edges around the terminals of the strands to a distance approximately midway of their length as indicated at 5, the plates being

55 provided at said central portion with parallel opposed ears 6. The ears of one plate

are adapted to be disposed between the ears of the opposite plate and all pivotally connected by means of a pintle 7 penetrating apertures provided in the ears. The members are thus pivoted together for relative movement, permitting spacing of the curved portions 2 of the jaws to grip articles there- 60 between.

A plate 8 formed of a strip of resilient 65 metal is bent substantially in the form of the letter U, the intermediate portion of which is engaged about the pintle 7 and the terminals thereof bearing against the inner sides of the plates 4. In this manner the operating ends of the clasp are urged apart and the curved portions 2 of the clamping jaws normally held in contact. If desired 70 the plates may be provided with apertures 9 to permit the clasp to be suspended from 75 a hook or the like when an article of clothing is held between the jaws.

In Fig. 5 of the drawings I have illus- 80 trated a clasp which is constructed in a manner identical with the form just described except for the substitution of a means for retaining the jaws in clamped relation. This means comprises a section of wire 10 engaging around the pintle 7 with its terminals at right angles as at 11 to 85 firmly bear against the under sides of the plates 4. The operation of this form of clasp is otherwise the same as the foregoing.

Thus it will be seen that I have pro- 90 vided a simple form of clasp, which may be readily and cheaply constructed. The rounded ends of the jaws formed as they are of wire, preventing mutilation of articles of clothing which is the case when 95 clasps having serrated edges are employed. Other changes will be apparent as persons become familiar with their use.

While I have illustrated and described my invention with some degree of particularity, I realize that in practice various alterations 100 thereover may be made and I therefore reserve the right and privilege of changing the form of the details of construction, or otherwise altering the arrangement of the correlated parts without departing from the 105 spirit of the invention or the scope of the appended claim.

Having thus described my invention, what I claim as new and desire to secure by Letters Patent is:

110 A clasp comprising coacting relatively movable jaws, each formed of a strand of

wire U-shaped, a pair of plates, each having opposite edges extending around the terminals of one of the jaws to form a finger grip, apertured ears formed on said plates 5 at a point intermediate the ends of the jaws, a pintle entering said ears to pivot the jaws for relative movement, and a flat spring extending upon itself at a point intermediate its ends and engaged around the pintle, with 10 the terminals of said spring extending in

opposite directions to engage the inner side of the plates whereby to retain the bight portion of the jaws in clamped engagement.

In testimony whereof I affix my signature in presence of two witnesses.

RUBEN E. ROSENBERGER.
